INVENTOR

Erasmus D. Moss
BY *J. J. W. Robertson*
ATTORNEY.

UNITED STATES PATENT OFFICE.

ERASmus D. MOSS, OF DEFIANCE, OHIO.

TOOL-HOLDER.

SPECIFICATION forming part of Letters Patent No. 292,938, dated February 5, 1884.

Application filed August 8, 1883. (Model.)

To all whom it may concern:

Be it known that I, ERASmus D. MOSS, of Defiance, in the county of Defiance and State of Ohio, have invented new and useful Improvements in Tool-Holders; and I do hereby declare that the following is a full, clear, and exact description thereof, reference being had to the accompanying drawings, which form a part of this specification.

10. This invention relates to certain new and useful improvements in devices for holding drills while they are being ground; and the invention consists in the peculiar construction of an adjustable radial arm, and in the peculiar construction, arrangement, and combination of the various parts, all as more fully hereinafter set forth.

Figure 1 is a top plan of my invention. Fig. 2 is a side elevation of the same. Fig. 3 is a 20 vertical cross-section through the line $x-x$ of Fig. 2. Fig. 4 is a vertical section of part of the device on the line $y-y$, Fig. 1.

In the accompanying drawings, which form a part of this specification, A represents a 25 suitable table, semicircular in form, which is secured to the frame-work of a grindstone or emery-wheel by bolts through the slots B.

J is a radial arm pivotally secured at one 30 end to the bed-plate, at or about the center of the straight side thereof, by a bolt, J'. On this table, near the center of its straight edge, is a raised piece, J², the object of which is to raise the arm J from the table and allow it to be freely moved from side to side. This arm 35 J is provided with a locking-clamp, O, consisting of a plate secured to said arm by a screw, o', by means of which said arm is secured to its adjusted position upon the bed-plate by turning the hand-screw o, which fits 40 a tapped hole in the clamp O.

K is a slotted post sleeved upon the arm J,

and is capable of being adjusted thereon to suit varying lengths of drill to be ground, being secured to its position by a set-screw, a.

L is a flanged sleeve having an internal 45 thread, and provided with a squared portion, b, which passes through the vertical slot in the post K, and is threaded on the exterior of its outer end to receive a binding-nut, M.

D is a threaded center which passes through 50 the sleeve L.

H is a rest secured to the front edge of the table, and upon the inner edge of this rest is the stop G.

In practice the drill is held back against the 55 center-point D, while the cutting-edge of the drill is held in contact with the stone or emery-wheel N, and it is ground away by crowding the tool edgewise against the stone in the direction of the arrow until the tool is arrested 60 by contact with the stop G. When both edges of the tool have thus been ground, they will be alike in size and angle, and the point will be central.

The radial arm can easily be adjusted so 65 that the tool may be presented to the stone from either side, as desired.

What I claim as my invention is—

1. In combination with the table A, the adjustable radial arm J, post K, and center D, 70 adjustable on said post, substantially as and for the purposes set forth.

2. In combination with the table A, the radial arm J, slotted post K, center D, adjustable vertically on said post, and rest H, when 75 constructed, arranged, and operating substantially in the manner and for the purposes specified.

ERASmus D. MOSS.
